Charles H. Frost. Design for Stoves.

Patented April 29, 1862.

Dec. 1568

Charles H. Frost, of Peekskill, N. Y.
Letters Patent No. 1568, dated Apr. 29, 1862.

The schedule referred to in these Letters Patent and making part of the same.

To all whom it may concern:

Be it known that I, Charles H. Frost, of Peekskill, Westchester County, New York State, have invented a new and original design for a Cooking Stove or Range, and I do hereby declare that the following is a full and exact description of the same reference being had to the accompanying drawings and the letters marked thereon.

A. fig. 1. represents a front, B, an end view of the stove or range. C represents the oven door on which D, represents a rope moulding in the form of an oval, in the centre of which the word Monitor is carved - the letters enlarging from the ends to the centre of the word as shown.

The edge of the oven door is finished with an O. G. moulding, E represents the fire door carved similar to the oven door, except that a figure indicating the diameter of the pot holes adorns the centre of the oval. F represents the door of the ash pit on which at the bottom is a moulding like that at the edge of the hearth, and G, represents a panel at the angles of the perpendicular sides of the stove, which panel is a quarter of a circle surrounded by a half round bead moulding. H, represents a rope moulding, corresponding in form to that on the oven door, in a panel surrounded by a half O. G. moulding I.

K, represents an O. G. moulding around the hearth, on which the following letters are carved - "Frost and Southard Peoples Stove Works Peekskill N. Y." The top of the stove is formed as indicated by the drawing with an O. G. moulding around each side, the back of the stove and the opposite end need no further description.

What I claim as my invention, and desire to secure by Letters Patent is -

The combination of mouldings as set forth.
